UNITED STATES PATENT OFFICE

2,453,515

RESTRAINING MECHANISM FOR FREE-PISTON UNITS

Andrew Kalitinsky, Eagleville, Conn., assignor to
United Aircraft Corporation, East Hartford,
Conn., a corporation of Delaware

Application November 6, 1944, Serial No. 562,249

6 Claims. (Cl. 74—57)

1

The opposed pistons of a free-piston unit are normally maintained at equal distances from the center of the engine by a restraining linkage. The copending application of Ward, Serial No. 562,248, filed November 6, 1944, has a linkage including a sleeve having right and lefthand threads engaging with corresponding high-pitch threads on rods extending from the pistons. A feature of this invention is the use of a pair of interconnected sleeves, each of which is threaded for engagement by one of the pair of rods extending from the opposed pistons.

Another feature is the interconnection of the sleeve so that the sleeves may be similarly threaded. One of the sleeves may carry a cam for actuating an engine accessory. One feature of the invention is the use of the two sleeves to permit a longer piston stroke without seriously lengthening the unit, since the ends of the rods may pass each other during operation of the unit.

The rate of piston reciprocation is determined primarily by the mass of the moving elements of which the restraining linkage forms a part. A feature of this invention is a linkage, the weight of which is easily changed for varying the rate of piston reciprocation. The pair of sleeves, which oscillate as the pistons reciprocate may be relatively heavy, if desired, for a slow rate of piston reciprocation.

Other objects and advantages will be apparent from the specification and claims, and from the accompanying drawing which illustrates what is now considered a preferred embodiment of the invention.

Fig. 1 is a sectional view through the free-piston unit.

Fig. 2 is a fragmentary sectional view of the restraining mechanism.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10. Air compressed in the air spring cylinders on the power stroke returns the piston assemblies.

Intake manifold 34 conducts air to intake valves 36 through which air alternately enters opposite ends of the compressor cylinders. The compressed air leaves the cylinders through discharge valves 38, also at opposite ends of the

2

compressor cylinders, and passes through scavenging manifold 40 through ports 42 and 44 which are uncovered by pistons 12 and 14 at the end of the power stroke, thereby permitting air to be blown through the engine cylinder. Gas from the engine cylinder discharges through exhaust ports 46 and 48 into exhaust manifold 50.

A mechanism interconnects the piston assemblies to maintain them always at equal distances from the center of the engine cylinder. The linkage shown includes spaced parallel sleeves 52 and 54 rotatably supported by bearings 56 and 58 and having interengaging gear teeth 60 and 62 for simultaneous rotation. Sleeves 52 and 54 have internal high-pitch thread grooves 64 and 66 engaging with threads 68 and 70 on rods 72 and 74 extending from compressor pistons 16 and 18. If either piston assembly tends to move out of phase, it is prevented by the interconnected sleeves.

Either set of gear teeth 60 or 62 may drive accessories such as the fuel pump or a cam 76 may be mounted on either of sleeves 52 or 54 for driving an accessory, not shown.

The rate of piston reciprocation in a free-piston unit is dependent primarily upon the weight of the moving masses of the unit. Since the sleeves, which oscillate as the pistons reciprocate, constitute a part of the moving mass, the rate of reciprocation of the unit may be adjusted by changing the weights of these sleeves.

Although only one restraining linkage has been described, it will be understood that a pair of these linkages may be used for balancing the restraining action on the opposed pistons.

It is to be understood that the invention is not limited to the specific embodiment herein illustrated and described, but may be used in other ways without departure from its spirit as defined by the following claims.

I claim:

1. A free-piston unit having opposed pistons, in combination with a restraining mechanism for said pistons, including a pair of rods, one extending from each of the opposed pistons, a pair of rotary sleeves, one for each rod, said sleeves having interengaging means for rotation in unison and interengaging threads on the sleeves and the associated rods for turning the sleeves as the rods are reciprocated with the pistons.

2. A free-piston unit having opposed pistons, in combination with a restraining mechanism for said pistons, including a pair of rods, one extending from each of the opposed pistons, a pair of rotary sleeves, one for each rod, said sleeves having

interengaging means for rotation in unison and interengaging threads on the sleeves and the associated rods for turning the sleeves as the rods are reciprocated with the pistons, one of said sleeves having accessory actuating means thereon.

3. A restraining mechanism for the opposed pistons of a free-piston unit, said mechanism including a pair of rods, one extending from each piston, a pair of rotary sleeves, one for each rod, said sleeves being parallel to each other and having interengaging means for rotation in unison, interengaging threads on the rods and sleeves for turning the sleeves as the rods are reciprocated with the pistons and means for supporting the sleeves in fixed axial position.

4. A restraining mechanism for the opposed pistons of a free-piston unit, said mechanism including a pair of rods, said rods being parallel, and one extending from each piston, a pair of rotary sleeves, one for each rod, said sleeves having interengaging means for rotation in unison, interengaging threads on the sleeves and the associated rods for turning the sleeves as the rods are reciprocated with the pistons and means for supporting the sleeves in fixed axial position.

5. A restraining mechanism for the opposed pistons of a free-piston unit, said mechanism including a pair of parallel rods extending toward each other from the opposed pistons, a pair of sleeves engageable by said rods, said sleeves having interengaging means for rotation in opposite directions, each sleeve having similarly arranged threads thereon, cooperating threads on the associated rods for turning the sleeves as the rods are reciprocated with the pistons and means for supporting the sleeves in fixed axial position.

6. A restraining mechanism for the opposed pistons of a free-piston unit, said mechanism including a pair of parallel rods extending toward each other from the opposed pistons, a pair of sleeves engageable by said rods, said sleeves having interengaging means for rotation in opposite directions, each sleeve having similarly arranged threads thereon, cooperating threads on the associated rods for turning the sleeves as the rods are reciprocated with the pistons, one of said sleeves having a cam for actuating an accessory for the unit and means for supporting the sleeves in fixed axial position.

ANDREW KALITINSKY.
